UNITED STATES PATENT OFFICE.

ALFRED L. SALVO, OF AUGUSTA, GEORGIA.

FLYING TOY.

1,420,449.

Specification of Letters Patent. Patented June 20, 1922.

Application filed February 1, 1922. Serial No. 533,416.

To all whom it may concern:

Be it known that I, ALFRED L. SALVO, citizen of the United States, residing at Augusta, in the county of Richmond and 5 State of Georgia, have invented certain new and useful Improvements in Flying Toys, of which the following is a specification.

This invention relates to toys, having more particular reference to a toy comprising a 10 helix adapted to be projected into the air by the imparting of rapid revolving motion thereto.

The invention has for an object to provide a novel and inexpensive toy of the this 15 type whereby a high velocity may be applied by manually operated means to the helix to project the latter a considerable distance into the air.

For further comprehension of the invention, and of the objects and advantages thereof, reference will be had to the following description and accompanying drawings, and to the appended claims in which the various 20 novel features of the invention are more particularly set forth.

Fig. 1 of the drawings is a detail perspective view of my improved toy.

Fig. 2 is a part side view and part axial sectional view thereof.

Fig. 3 is a fragmentary axial section showing a modified form of toy.

Fig. 4 is a like view showing another modification.

Referring now particularly to Figs. 1 and 2 of the drawings my improved toy comprises a handle 10 of substantially cylindrical outline having fixed to and projecting from its upper end, co-axially therewith, a rod 11.

Freely surrounding this rod is a sleeve 12 which rests upon the upper end of the handle, disengagement of the sleeve 12 from the rod 11 being prevented by a head 13 on the rod which is located in an enlargement at the 45 upper end of the bore of the sleeve.

This sleeve 12 serves as the support upon which the helix 15 is placed, the sleeve having a pair of upwardly projecting pins 16 which are adapted to project through holes 50 17 in the hub of the helix to cause the latter to rotate with the sleeve.

The helix 15 may be conveniently made of sheet metal stamped to proper shape, the helix here shown being of the four bladed 55 type, although any suitable number of blades may be employed.

Rotation is imparted to the sleeve 12 by means of a cord 18 which is wound around a grooved portion 19 of the sleeve and is provided on one end with a button 20 to facilitate grasping when being pulled.

It is believed that the manner of use of my improved toy will be readily understood from the above description, the cord 18 being wound on the sleeve 12, the helix 15 placed on top thereof, the handle 10 grasped by one hand, and the cord pulled by the other, the rapid rotary movement imparted to the helix causing it to rise in the air for a considerable distance.

In Fig. 3 I have shown a modified arrangement in which the sleeve 12' is provided with a diminished upward projection 12^a on which the helix 15' rests, the latter being formed with a number of radial slots 23 into which project resilient pins or fingers 24 carried by the sleeve and presenting outwardly bowed upper portions 24' which yieldingly hold the helix on the sleeve. In this arrangement, when the sleeve is spun, 80 the helix is held in place until it attains sufficient speed to develop a lifting force sufficient to overcome the resistance of the spring pins 24.

In Fig. 4 I have shown a further modification in which a pair of resilient fingers 28 are fixed at one end in the sleeve 12^b and project longitudinally outwardly through radial slots 29 therein and through radial slots 30 in the helix 15^b, having hooked 90 free ends 28' which engage over the helix and hold it on the sleeve 12^b when the rods are pressed inwardly by winding the cord 18' on the sleeve.

When the toy is spun these rods 28 remain in operative position until the cord is unwound, when they spring outward and release the helix.

Having thus described my invention what I claim as new and desire to protect by 100 Letters Patent of the United States is as follows:

1. A toy comprising a handle, a rod projecting therefrom, a sleeve swiveled on said rod, a helix seating on said sleeve and having apertures through which said pins project, and resilient fingers carried by said sleeve and yieldingly gripping said helix to hold the latter against axial movement with respect to said member during initial 105 rotary movement of the helix, said helix being adapted to be automatically disen-

gaged from said fingers by pressure thereof in an axial direction against the latter caused by rotation of the helix at high speed.

2. A toy comprising a handle, a member rotatably mounted thereon, a helix seating on said member, and resilient gripping means carried by said member and engaging said helix to hold it against axial movement with respect to said member during initial rotary movement of the helix, said helix being adapted to be automatically disengaged from said gripping means by pressure thereof in an axial direction against the latter caused by rotation of the helix at high speed.
- 10 3. A toy comprising a handle, a sleeve rotatable on said handle, a helix seating freely but non-rotatably on said sleeve, and resilient gripping elements yieldingly engaging said helix to hold the latter against
- 15

axial movement with respect to said sleeve 20 during initial rotary movement of the sleeve, said helix being adapted to be automatically disengaged from said gripping elements by pressure thereof in an axial direction against the latter caused by rotation of the helix 25 at high speed.

4. A toy comprising a handle, a sleeve rotatable on said handle, and a helix seating freely but non-rotatably on said sleeve, and means other than gravity holding said helix 30 on said sleeve during initial rotary movement of said sleeve, said means comprising resilient fingers projecting through radial slots in said helix and engaging the slot walls.

In testimony whereof I have affixed my signature.

ALFRED L. SALVO.
